UNITED STATES PATENT OFFICE.

JOHN N. SPEREKAS, OF HAMILTON, OHIO, ASSIGNOR OF ONE-HALF TO JOHN L. BLACK,
OF HAMILTON, OHIO.

DEVICE FOR POLISHING SHOES.

1,307,276.

Specification of Letters Patent. Patented June 17, 1919.

Application filed June 26, 1918. Serial No. 242,059.

To all whom it may concern:

Be it known that I, JOHN N. SPEREKAS, a citizen of the United States, residing at Hamilton, in the county of Butler and State 5 of Ohio, have invented new and useful Improvements in Devices for Polishing Shoes, of which the following is a specification.

This invention relates to new and useful improvements in devices for polishing shoes 10 and the principal object of the invention is to provide a brush revolved by an electric motor with means for movably connecting said brush with the motor shaft.

Another object of the invention is to provide a device of this character which is 15 simple and durable in construction, reliable and efficient in operation and one which can be manufactured and placed upon the market at a minimum cost.

20 The invention also consists in certain other features of construction and in the combination and arrangement of the several parts, to be hereinafter fully described, illustrated in the accompanying drawings and 25 specifically pointed out in the appended claims.

In describing my invention in detail, reference will be had to the accompanying drawings wherein like characters denote like 30 or corresponding parts throughout the several views, and in which:—

Figure 1 is an elevation of the invention. Fig. 2 is a like view with parts in section. Fig. 3 is a transverse section on line 3—3

35 of Fig. 1. Fig. 4 is an end view of the shield and brace part.

Fig. 5 is an elevation partly broken away, 40 of a fanning device connected with the motor.

Fig. 6 is an end view of the fanning device.

As shown in these views the invention includes a casing 1 in which is located an electric motor of any desired form. The shaft 2 of said motor projects from one end of the casing and is provided with a transverse pin 3 adjacent its outer end. A handle 4 is connected with the other end of the casing 50 and the circuit wires 5 for the motor pass through said handle. One of said wires passes to the motor while the other is connected with one of a pair of contacts 6, the remaining contact being connected with the 55 motor. These contacts are bridged by the

wedge shaped lower end 7 of a push button 8 mounted in said handle. 9 indicates the circular brush removably secured to a hollow shaft 10 by means of the washer 11 and the nut 12 which engages the end of the 60 shaft. Said hollow shaft 10 is provided with a slot 13 which extends longitudinally from the opposite end of said shaft to within a short distance of said brush. The walls of said slot are grooved so that the 65 motor shaft 2 may be placed within said slot with the pin 3 engaging the outer walls thereof. In this manner when the motor operates the shaft of the brush will be caused to revolve with the motor shaft. A 70 shield 14 is rotatably carried by the brush shaft 10, said shield being of cylindrical form and having its ends covered by end pieces 15 made of a plurality of small bars 75 spaced apart and extending across said ends at right angles to each other. These bars support a ring 17 forming a bearing for the shaft 10.

18 indicates a collar secured to the shaft 10 for holding the shield in place. It will thus be seen that the hollow shaft for the brush simply slides over the motor shaft and is adapted to be held thereon by the hand of the user grasping the shield. When the 80 device is to be used the handle is grasped in one hand and the shield is held by the other hand, then by pressing on the button 8 the connection to the motor will be complete and the same caused to revolve. In this manner the brush will be revolved to brush the shoe. 85 It will be seen that the brush may be moved toward and away from the motor by means of the shield as the motor shaft will continue to revolve the brush shaft as long as the pin 3 is located within the slot 13. When 90 desired the brush may be replaced by the fan attachment 19. This attachment consists of the circular casing or shield 20 provided with the slotted shaft 21 similar to the slotted shaft just described and adapted to receive the motor shaft. The fan blade 22 is secured to the end of said shaft and the casing 20 is extended to surround said blade so as to prevent the clothing coming in contact with said fan. The inner end of the casing 105 is provided with the end piece as before described so that the air may readily pass through said casing. In other respects this attachment is similar to that just described and operates in the same manner. This at- 110

tachment may be used for the drying of shoes.

It will be seen that the combined handle and shield surrounds the parts lying between the brush head and the casing of the motor and thus acts to prevent the clothing from coming into contact with these parts.

It is thought from the foregoing description that the advantages and novel features 10 of my invention will be readily apparent.

I desire it to be understood that I may make such changes in the construction and in the combination and arrangement of the several parts as desired, provided that such 15 changes fall within the scope of the appended claims.

What I claim is:—

1. A device of the class described comprising a casing, a motor within the casing, a 20 motor shaft projecting from the casing, a transverse pin in the end of said shaft, a slotted hollow shaft having the slot extending

through its end for removably engaging the motor shaft, a member to be rotated connected to said slotted shaft and a cylindrical member forming a combined handle and shield rotatably carried by the slotted shaft whereby said shaft may be movably held on the motor shaft and removed therefrom. 25

2. A device of the class described comprising a casing, a motor within the casing, a motor shaft projecting from the casing, a transverse pin in the end of said shaft, a slotted hollow shaft adapted to fit over the motor shaft, a brush connected with said 30 slotted shaft, a cylindrical member forming a combined handle and shield rotatably carried by the slotted shaft and a collar on the inner end of the slotted shaft for holding the cylindrical member between itself and the 35 brush.

In testimony whereof I affix my signature.

JOHN N. SPEREKAS.
